Attorney, Agent, or Firm—Jones & Askew

[57] CLAIM

The ornamental design for a snack tray, as shown and described.

DESCRIPTION

FIG. 1 is a perspective view showing a first embodiment of my snack tray;

FIG. 2 is a top view thereof;

FIG. 3 is a bottom view thereof;

FIG. 4 is a front view thereof, the rear view being a mirror image;

FIG. 5 is a right side view thereof, the left side view being a mirror image;

FIG. 6 is a perspective view showing a second embodiment of my new snack tray;

FIG. 7 is a top view thereof;

FIG. 8 is a bottom view thereof;

FIG. 9 is a front view thereof, the rear view being a mirror image;

FIG. 10 is a right side view thereof, the left side view being a mirror image;

FIG. 11 is a perspective view showing a third embodiment of my new snack tray;

FIG. 12 is a top view thereof;

FIG. 13 is a right side view thereof;

FIG. 14 is a front view thereof;

FIG. 15 is a bottom view thereof;

FIG. 16 is a rear-view thereof; and,

FIG. 17 is a left side view thereof.

This is a continuation-in-part of Ser. No. D5,163 filed Feb. 25, 1993.
